(57) **CLAIM**

The ornamental design for a wiper blade airfoil, as shown and described.

DESCRIPTION

FIG. 1 is a perspective view of the wiper blade airfoil design of the present invention;

FIG. 2 is a top view thereof;

FIG. 3 is a left side view thereof;

FIG. 4 is a right side view thereof;

FIG. 5 is a bottom view thereof; and

FIG. 6 is an end view thereof; and,

FIG. 7 is a view of the opposite end thereof.
